HYDRAULIC PRESS FOR STEPWISE
DRAWING OF METAL

Robert A. Kaser, Dayton, Ohio, assignor to The
Hydraulic Development Corporation, Inc., Wil-
mington, Del., a corporation of Delaware

Application December 11, 1942, Serial No. 468,874

8 Claims. (Cl. 60—52)

1

This invention relates to hydraulic machinery and, in particular, to control mechanism for a reciprocable plunger to control the advancement thereof in steps. The invention may advantageously be used in connection with drawing presses for performing deep drawing strokes.

In order to permit step-wise deep drawing on a single press, it has been suggested to arrange in the base of a crank-type mechanical press a hydraulic cylinder-piston-assembly and to control the latter so that a die carried thereby and operating with the drawing punch, is lifted by a predetermined distance each time the punch has performed an advancing and a retraction stroke.

To hold the work piece clamped against the bed during this drawing operation, it has been suggested to provide the mechanical press with a hydraulically operated clamping platen. However, since this type of press requires not only the complete mechanical drawing mechanism, but also a number of parts and control means which are standard equipment with hydraulic presses, the above mentioned hydro-mechanical deep drawing presses are relatively expensive and complicated.

It is, therefore, an object of this invention to provide control means for use in connection with a fluid operable plunger, such as a press ram, which will cause said plunger to perform a plurality of successive advancing and retracting strokes, while simultaneously causing said plunger to move closer to a fixed point, for instance a work piece, with each successive advancing stroke.

It is another object of this invention to provide a hydraulic drawing press in which the press ram is hydraulically advanced in one and the same direction in steps, and in which, following each step, the press ram is retracted by a distance less than the total advancing stroke preceding said retraction stroke.

Still another object of the invention consists in the provision of a drawing press as set forth in the preceding paragraph, in which the distance by which the press ram is being advanced during each step may be varied.

These and other objects and advantages of the invention will appear more clearly from the following specification in connection with the accompanying drawings, in which:

Figure 1 illustrates the control mechanism according to the invention in connection with a hydraulic drawing press.

Figure 2 illustrates the wiring diagram for control means associated with the press shown in Figure 1.

Figure 3 shows a detail of Figure 1.

General arrangement

In general, the control mechanism shown in

2

the drawings comprises a reciprocable element which, in response to a predetermined advancing stroke of the press ram, actuates a limit switch to thereby initiate the reversal of the press ram.

When pressure fluid is being admitted to the ram for retracting the same, a portion of this pressure fluid operates means for actuating said reciprocable element so that the latter, in response to a predetermined retraction stroke of the ram, less than the preceding advancing stroke thereof, initiates a new advancing stroke of said ram, which new advancing stroke will be larger than the preceding retraction stroke. At the end of this advancing stroke, the reciprocable element again actuates the said limit switch, to thereby initiate a retracting stroke of the ram in the same manner as mentioned before.

The cycle is then repeated until the work piece has been drawn to its desired depth, at which time the press ram is completely retracted to its initial starting position.

Structural arrangement

Referring now to the drawings in detail, the system shown therein comprises a press cylinder 1 having reciprocably mounted therein a press ram 2. Connected to the press ram 2 is a press platen 3 carrying a punch 4 adapted, in cooperation with the die 5, to shape a work piece, such as a metal sheet 6. Blankholder means 7 is provided for clamping the marginal portion of the metal sheet 6 against the adjacent portion of the die 5. The clamping means 7 may be clamped against the work piece 6 by any standard clamping mechanism.

The press platen 3 is provided with an arm 8 adapted to engage a collar 9 adjustably mounted on a push rod 10. The push rod 10 has mounted thereon a collar 11 adapted to engage a three-arm lever 12, which latter is adapted to shift about a pivot 13. The arm 14 of the lever 12 is pivotally connected with an armature 15 controlled by a solenoid 16 in such a manner that energization of the solenoid 16 causes the armature 15 to move downwardly, thereby shifting the three-arm lever 12 in counter-clockwise direction and causing the linkage 17 connected thereto to bring about movement of the pump 18 into full delivery advancing stroke position. The pump 18 may be a reversible variable delivery pump of any standard design and may be either of the radial piston or the radial vane type.

One side of the pump 18 is connected through the conduit 19 with the upper portion of the press cylinder 1, while the other side of the pump 18 is connected through the conduit 20 with the lower portion of the press cylinder 1. Connected with the conduit 19 is a conduit 21 leading to a tonnage control valve 22 of any standard design which, in response to a predetermined pres-

sure in the conduit 51, closes a normally open switch 51a (see Figure 2).

Branching off from the conduit 29 is a pilot line 21 comprising a check valve 22 adapted to admit pressure fluid from the fluid reservoir or tank 23 into the conduit 21, while preventing the flow of fluid in the reverse direction. Branching off from the conduit 21 is a pilot line 26 leading to a surge valve 25. The surge valve 25 is adapted in response to a predetermined pressure in the conduit 24 to open, thereby establishing fluid connection between the tank 23 and the upper portion of the press cylinder 1. The surge valve 25 also opens in response to a suction effect in the upper portion of the press cylinder 1.

Connected with the lower portion of the press cylinder 1 is a further pilot line 26 leading into one end of a control cylinder 27 (see Figure 3), having reciprocably mounted therein a piston 28. The piston 28 is continuously urged into its left hand position, with regard to Figure 3, by a spring 29, having one end in abutment with the piston 28, while the other end abuts the right hand wall of the cylinder 27. An exhaust line 30 connects the right hand portion of the cylinder 27 with the tank 23.

Connected to the left side of the piston 28 is a piston rod 31 carrying an adjustable abutment nut 32 for abutment with the left side of the cylinder 27. Connected with the right hand side of the piston 28 is a rod 33 carrying a pawl 34 for cooperation with a ratchet 35. As will be clear from Figure 3, rightward movement of the piston 28 causes the pawl 34 to engage one of the teeth of the ratchet 35, and to rotate the ratchet 35 by a predetermined angle, depending on the stroke of the piston 28. The maximum stroke of the piston 28 is determined by the distance between the right end of the abutment nut 32 and the left side of the cylinder 27.

Slidably passing through the ratchet 35, but keyed thereto, is a rod 36 forming an extension of the spindle 37, which latter has adjustably mounted thereon a collar 38 for cooperation with a normally closed limit switch LS2. The collar 38 is adapted to engage and thereby to open the limit switch LS2. The rod 36 is adapted to engage and close the normally open limit switch LS1. The spindle 37 threadedly engages nut portions 39 and 40 connected to a slide 41, which is slidably mounted on and guided by a stationary guide 42. The nut portions 39 and 40 are adapted alternately to be engaged by the platen arm 8a.

The spindle 37 is furthermore provided with a keyway 43 engaged by a key (not shown), which key is provided in the beveled gear 44 for connecting the same with the spindle 37, so that rotation of the gear 44 will rotate the spindle 37. The spindle 37 is slidable in the gear 44. The beveled gear 44 is engaged by a beveled gear 45, which latter is rotated by means of the hand wheel 46, and is journaled in an extension 47 of the guide 42.

The spindle 37 has also adjustably mounted thereon a collar 48 engaged by the upper portion of a spring 49, the lower portion of which is supported by a support 50. The spring 49 fleetingly supports the spindle 37.

Referring now to the wiring diagram of Figure 2, the same shows the main supply line 53 connected with the line 54, which latter is adapted, by closure of the tonnage control switch 52a through line 55 and contactor A to be connected with the main supply line 56. Energization of

the contactor A causes the contactor switch A1 to open and the contactor switch A2 to close, while deenergization of the contactor A causes the contactor switch A1 to close and the contactor switch A2 to open. When the contactor switch A2 is closed, it establishes electric connection between the line 55 and the main supply line 53 through the normally closed reset switch 60. When the contactor switch A1 and the starter switch 57 are closed, the main supply line 53 is connected through lines 58 and 59 and the contactor B with the main supply line 56.

Energization of the contactor B causes the normally open switches B1 and B2 to close. Closure of the switch B2 connects the main supply line 53 with the solenoid 16, while closure of the contactor switch B1 connects the lines 61 and 62 with each other.

The line 62 is connected through the line 63 with the line 58 and is adapted by closure of the limit switch LS1 to be connected with the main supply line 53. The line 61 is adapted to communicate through the normally closed switch LS2 with the main supply line 53.

Operation

It may be assumed that the press ram 2 is in its fully retracted position, in which the push rod 10, by means of the lever 12 and linkage 17, holds the pump 18 in substantially neutral or no delivery position.

It may also be assumed that the work piece 6 is properly clamped between the blankholder means 7 and the adjacent portion of the die 8.

If it is now desired to perform a deep drawing stroke, the operator closes the starter switch 57, thereby closing the energizing circuit for the contactor B through the normally closed contactor switch A1. Energization of the contactor B causes the contactor switches B1 and B2 to close. Closure of the contactor switch B1 establishes a holding circuit for the contactor B, which holding circuit comprises the main supply line 53, normally closed limit switch LS2, now closed switch B1, lines 62, 63, 58, switch A1, contactor B and the main supply line 56. The contactor B, therefore, remains energized when the switch 57, after its release by the operator, again opens.

Closure of the contactor switch B2 closes the energizing circuit for the solenoid 16, so that the latter moves the armature 15 downwardly and, through the lever 12 and linkage 17, shifts the pump 18 into forward delivery position. Pressure fluid from the pump 18, therefore, flows through conduit 19 into the upper portion of the cylinder 1, while fluid from the lower portion of the cylinder 1 is withdrawn through conduit 20. The ram 2, therefore, moves downwardly by gravity as fast as fluid is withdrawn from the lower portion of the press cylinder 1.

During the first portion of the downward stroke of the ram 2, the fluid delivered by the pump 18 through the conduit 19 is supplemented by fluid passing from the tank 23 through the surge valve 25, which latter is open at this time, due to the suction effect created in the upper portion of the press cylinder 1.

When the punch 4 engages the work piece 6, pressure begins to build up in the upper portion 70 of the cylinder 1, causing the surge valve 25 to close. The ram 2 now begins its actual drawing stroke.

When the punch 4 has moved downwardly a predetermined distance, the arm 8a engages the nut portion 49. Further downward movement of

the punch 4 to a position indicated by the dot-dash line 64, has caused the spindle 37 to move downwardly to such an extent that the collar 38 has opened the limit switch LS2. Opening of the limit switch LS2 breaks the holding circuit for the contactor B, so that the contactor switches B1 and B2 open. Opening of the contactor switch B1 has no additional effect at this time.

Opening of the contactor switch B2 causes de-energization of the solenoid 16, so that a spring (not shown), which is provided in the servomotor 65 associated with the pump 18, causes the pump 18 to move into its full delivery retraction stroke position. Consequently, pressure fluid delivered by the pump 18 now passes through the conduit 20 into the lower portion of the cylinder 1, while simultaneously opening the surge valve 25. The ram 2, therefore, begins to move upwardly. Pressure fluid admitted to the lower portion of the press cylinder 1 is also conveyed through the pilot line 26 into the left hand portion of the cylinder 27, where it acts upon the piston 28 and causes the same to move the rod 33 and the pawl 34 toward the right. This movement of the pawl 34 causes the ratchet 35 to rotate in anti-clockwise direction, with regard to Figure 3, so that the spindle 37 performs a corresponding rotation. This rotation of the spindle 37 causes the slide 41 to move downwardly a predetermined distance.

When the platen arm 8a, during the upward movement of the ram 2 just described, engages the nut portion 39, it begins to lift the spindle 37 and, thereby, also the extension rod 36. When the spindle 37 has been lifted a predetermined distance, the rod 36 closes the limit switch LS1.

Closure of the limit switch LS1 establishes an energizing circuit for the contactor B, which circuit comprises the main supply line 53, now closed switch LS1, lines 63 and 68, contactor switch A1, line 69, contactor B and the main supply line 56. Consequently, the contactor B is energized and again closes the contactor switches B1 and B2, with the result that, as described above, the solenoid 16 is energized.

As likewise described above, energization of the solenoid 16 shifts the pump 18 again on forward stroke and the ram 2 again moves downwardly. Since, however, as mentioned above, the slide 41 was moved downwardly from the position it previously occupied, the platen arm 8a will not engage the nut portion 40 at the same point at which it previously engaged the said nut portion, but will have to travel further downwardly before it again engages said nut portion 40 and, thereby, in the same manner as described above, initiates another partial retraction stroke of the ram 2. The cycle described above is then successively repeated through the stages indicated in dot-dash lines 66, 67 and 68.

When the punch 4 has reached the position corresponding to the dot-dash line 68, the work piece 6 has been drawn to its desired shape and the pressure now developed in the upper portion of the press cylinder 1 and conveyed through the conduit 19 to the tonnage control valve 52, causes the tonnage control switch 52a to close. As a result thereof, the contactor A is energized. Closure of the contactor A causes the contactor switch A1 to open and the contactor switch A2 to close.

Closure of the contactor switch A2 establishes an energizing circuit for the contactor A, whereas opening of the contactor switch A1 breaks the energizing circuit for the contactor B. De-energization of the contactor B causes the con-

tactor switches B1 and B2 to open. While the opening of the contactor switch B1 has no effect at this time, the opening of the contactor switch B2 causes de-energization of the solenoid 16 so that the spring, previously referred to in the servomotor 65, causes the pump 18 to move into full delivery retraction stroke position. In the manner described above, the pump 18 now delivers pressure fluid to the lower portion of the press cylinder 1 and causes the press ram 2 to move upwardly.

Inasmuch as the contactor A remains energized and, therefore, the contactor switch A1 remains open, the contactor B will not be energized when the spindle 37, during the present upward movement of the ram 2, is lifted and causes the rod 36 to close the limit switch LS1.

When the press ram 2 has reached the end of its retraction stroke, the push rod 19 has shifted the lever 12 into such a position that the linkage 11 has moved the pump 18 into substantially neutral or no delivery position. Consequently, no fluid is conveyed to or withdrawn from the press cylinder 1 and the ram 2 comes to a stop. To restore the previous position, the operator resets the spindle 37 by rotating the hand wheel 46. Thereafter, the reset switch 66 is temporarily opened to de-energize the contactor A. All the parts are now at their initial position and, after replacement of the workpiece, a new work cycle may be started.

It will be understood that I desire to comprehend within my invention such modifications as come within the scope of the claims.

Having now fully described my invention, what I claim as new and desire to secure by Letters Patent is:

1. In a hydraulic system; a reciprocable plunger having advancing and retracting means, first and second control means operable to direct actuating fluid to said advancing means or to said retracting means, respectively; a pair of spaced means operated respectively by said plunger at the end of the retraction stroke and at the end of the advancing stroke for automatically making first one and then the other of said control means effective for automatically reciprocating said plunger between predetermined limits; and means operated by the supply of fluid to said retracting means for adjusting both of said spaced means a predetermined distance in said advancing direction.
2. In a hydraulic system; a reciprocable plunger having advancing and retracting means, first and second control means operable to direct actuating fluid to said advancing means or to said retracting means, respectively; spaced means operated by said plunger for automatically actuating first one and then the other of said control means for automatically reciprocating said plunger between predetermined limits; means operated by the supply of fluid to said retracting means for adjusting both of said spaced means in the advancing direction a predetermined amount for continuously shifting said predetermined limits in said advancing direction; and means operable in response to a predetermined pressure on said advancing means for rendering ineffective said spaced means to permit a full retracting movement of said plunger.
3. In a hydraulic system; a reciprocable plunger having advancing and retracting means; first and second control means operable to direct actuating fluid to said advancing means or to said retracting means, respectively; a pair of

spaced means operated respectively by said plunger at the end of the retraction stroke and at the end of the advancing stroke for automatically making first one and then the other of said control means effective for automatically reciprocating said plunger between predetermined limits; means operated by the supply of fluid to said retracting means for adjusting both of said spaced means in the advancing direction a predetermined amount for continuously shifting said predetermined limits in said advancing direction; and means selectively operable initially to adjust said spaced means.

4. In a hydraulic system; a reciprocable plunger having advancing and retracting means; a fluid source for supplying said means; control means associated with said source operable to direct the delivery thereof to said advancing or to said retracting means; first means adapted for operation by said plunger at a predetermined point in its advancing travel for actuating said control means to bring about the supply of fluid to said retracting means; second means operated by said plunger at a predetermined point in its retracting movement for actuating said control means to bring about the supply of fluid to said advancing means; a threaded spindle supporting both of said first and second means rotatable simultaneously to adjust the position of said means; manual means for rotating said spindle; and means operable in response to the supply of actuating fluid to said retracting means for rotating said spindle a predetermined amount.

5. In a hydraulic system; a reciprocable plunger having advancing and retracting means; first and second control means operable to direct actuating fluid to said advancing means or to said retracting means, respectively; a threaded rod yieldably supported parallel with the path of said plunger; spaced cooperating abutment means carried by said plunger and by said threaded rod for moving said rod in response to predetermined movements of said plunger in opposite directions; first switch means adapted for operation by said rod when the latter moves upwardly for actuating said first control means; second switch means adapted for actuation by said rod when the latter moves downwardly for actuating said second control means; manually operable means for turning said rod initially to position the abutment means carried thereby; and fluid pressure responsive means connected with said retracting means operable in response to a predetermined pressure on said retracting means for rotating said rod through a predetermined angle to adjust the abutment means carried thereby a predetermined distance in the advancing direction of said plunger.

6. In a hydraulic system; a plunger having advancing and retracting means; a fluid source; first electrical means including a first switch operable to cause delivery of fluid from said source to said advancing means; second electrical means including a second switch operable to cause delivery of fluid from said source to said retracting means; a threaded rod yieldably sup-

ported adjacent said plunger and parallel to the path thereof; spaced abutment means carried by said rod; an abutment carried by said plunger adapted for engaging said spaced abutment means; cam means carried by said rod adapted for actuating said first switch in response to a predetermined upward movement of said rod and to actuate said second switch in response to a predetermined downward movement of said rod; indexing means carried by said rod for indexing the same through predetermined angles thereby to adjust the abutment means carried thereby in the advancing direction of said plunger; fluid pressure responsive means hydraulically connected with said retracting means operable to actuate said indexing means at the initiation of each retraction stroke; and means responsive to a predetermined pressure on said advancing means for rendering said first electrical means ineffective.

7. In a hydraulic system; a reciprocable plunger having advancing and retracting means, first and second control means operable to direct actuating fluid to said advancing means or to said retracting means, respectively; a pair of spaced means operated respectively by said plunger at the end of the retraction stroke and at the end of the advancing stroke for automatically making first one and then the other of said control means effective for automatically reciprocating said plunger between predetermined limits; and means responsive to the initiation of the retraction stroke of said plunger for adjusting both of said spaced means a predetermined distance in said advancing direction.

8. In a hydraulic system; a reciprocable plunger having advancing and retracting means, first and second control means operable to direct actuating fluid to said advancing means or to said retracting means, respectively; a pair of spaced means operated respectively by said plunger at the end of the retraction stroke and at the end of the advancing stroke for automatically making first one and then the other of said control means effective for automatically reciprocating said plunger between predetermined limits; and means operable automatically following the end of one working stroke and prior to the end of the following retraction stroke for adjusting both of said spaced means a predetermined distance in said advancing direction.
